UNITED STATES PATENT OFFICE.

ARTHUR L. SMITH, OF ST. PAUL, MINNESOTA.

METHOD OF MAKING EMBOSSED PRINTING.

No Drawing.

Application filed December 7, 1923. Serial No. 679,272.

This invention relates to a method of making embossed printing without the use of metal dies.

In accordance with the invention there is provided in place of the customary metal die a built-up male die formed of several sheets of paper, each sheet having a raised portion which is a counterpart of the embossing which is to appear on the finished job, the various sheets being superimposed on each other to give the desired depth of impression in the work to be embossed. The female die comprises a blotter.

The method of embossing the work and making the die is substantially as follows:

The work or letterheads to be embossed are first printed in the usual manner. The press is then allowed to print on the blanket or draw sheet after which a sheet of the same size as the printed work is put in the press and printed. This sheet will therefore have printing on its face and a printed reverse on its back face, both of said printings being exactly aligned. This procedure is repeated until the requisite number of sheets have been printed, say five sheets, though the number of sheets necessary will depend on the height of the embossing desired, as will presently appear. These sheets, with printing on the face and back, are then sprinkled on both sides with a powder comprising resin and damar, the powder adhering to the wet ink. The powdered paper is then heated, whereupon the powder particles melt and coalesce. Immediately on cooling to normal temperature the coalesced powdered material hardens. One of these sheets is then pasted to the platen of the press and a blotter is glued to a suitable metal base in the press. An impression is then pulled. The impression in the blotter, while not very deep, can be distinctly seen. The second of the prepared sheets (the powdered sheets) is then pasted directly over the first sheets and an impression again pulled. The impression in the blotter will be more pronounced than before. If additional depth of the impression is desired, then additional sheets, prepared as stated, are pasted on top of the sheets already in the press. The blotter and powdered paper constitute the embossing dies. The previously printed work is now run through the die, it being understood that the printing on the paper will be properly aligned with the die.

The powder, while preferably of the composition indicated, may be of other suitable material. The blotter is preferably of the kind known as 140-pound plain blotter.

By making the dies in the manner indicated, the cost of embossed work is very greatly reduced because of the elimination of the expensive metal dies heretofore used. The method of making the dies is very simple and can be made in the ordinary printing shop.

Having thus described my invention, what I claim as new and desire to secure by Letters Patent is:

1. The method of making embossing dies which consists in printing on the blanket of a press, placing a sheet of paper in the press and printing the same, coating the wet ink on the sheet with a powder which will harden, and forming the female die from a blotter into which the hardened powder on said sheet has been impressed.

2. The method of making a male die which consists in forming a raised surface on one side of a sheet of paper, said raised surface corresponding to the matter to be embossed, forming on the back of said sheet of paper a similar raised portion but which is in the reverse, said raised portions being in exact alignment, said raised portions being obtained by printing on both sides of the sheet and applying to the ink while wet a powder which will coalesce on the application of heat and harden at normal temperature.

3. Embossing dies comprising as the female die a sheet of blotting paper, the male die comprising a sheet of paper having a raised portion on both of its faces corresponding to the matter to be embossed, said raised portion consisting of a material adapted to soften in the presence of heat and harden at normal temperature.

4. The method of preparing dies for use in embossing consisting in making a printing impression on the blanket of a press, placing a sheet of paper within the press having printing thereon whereby both sides of the paper will receive a printing impression, sprinkling both sides of the sheet while the ink is wet with powder which will soften and coalesce on the application of heat, and harden at normal temperatures placing said sheet in a press and making an impression therefrom in a blotter, and superposing additional sheets similarly prepared on top of

the first sheet and making a further impression in said blotter, the embossing of the work being done by pulling the same through the dies.

- 5 5. A method of making dies consisting in providing a sheet of paper on both sides with perfectly registering characters, coating these characters with rosinous or other self hardening material, and heating the whole.
- 10 6. The herein described method of making dies, comprising the printing of an impression of the job on a pad secured to the bed of a printing press, covering said impression with a sheet of paper, printing another impression of the job on the front face

of the sheet in perfect register with the job printed on the pad, providing the rear face of the sheet with an impression of the job from the pad on the bed simultaneously with the printing of the front face, coating the impressions on both sides of the sheet with a rosinous material, heating the sheets for letting the wet imprints to rise, hardening the raised imprints, and finally combining a number of superposed sheets made by the same method to constitute a male die of a size required by the job.

In testimony whereof I affix my signature.

ARTHUR L. SMITH.
